UNITED STATES PATENT OFFICE.

GEORGE A. GRAVES, OF JOPLIN, MISSOURI, ASSIGNOR OF TWO-THIRDS
TO THOMAS W. CUNNINGHAM AND ALFRED REYNOLDS, OF JOPLIN,
MISSOURI.

CARBURETER FOR EXPLOSIVE-ENGINES.

SPECIFICATION forming part of Letters Patent No. 705,995, dated July 29, 1902.

Application filed October 16, 1901. Serial No. 78,689. (No model.)

To all whom it may concern:

Be it known that I, GEORGE A. GRAVES, a citizen of the United States, residing at Joplin, in the county of Jasper and State of Missouri, have invented new and useful Improvements in Carbureters, of which the following is a specification.

My invention relates to carbureters or mixing-valves for vapor or gas engines; and the object of the same is to construct a device of this character which will be simple in construction and efficient in operation. This object is accomplished by a simple and novel construction described in this specification and claimed, and illustrated in the accompanying drawings, forming a part thereof, in which—

Figure 1 is a vertical section of my device and a fragment of the cylinder. Fig. 2 is a detail of the gasoline-cup. Fig. 3 is a detail of the vaporizer.

Like numerals of reference designate like parts in the different views of the drawings.

25 The numeral 1 designates a hollow casing which forms a chamber for a needle-valve 2, mounted therein and having a threaded stem 3 and conical point 3^a. Connected to the casing 1 is a gasoline-supply pipe 4, an overflow-pipe 5, a vent-pipe 6, and a connection 7, having a valve-seat 8 in its inner end. The supply-pipe 4 is connected to some source of gasoline. (Not shown.) The outer end of the connection 7 is screwed into a vaporizing-chamber 9, which contains a valve-seat 10 and communicates with a cylinder 11 by way of a passage 12. Located within the chamber 9 and mounted in the end of the connection 7 is an annular cup 13, communicating with the 30 passage in the coupling 7 by means of a weir 14. A valve 15 fits the seat 10 and has a stem 16, which is slidingly mounted in the chamber 9 and passes through the central aperture in the annular cup 13. Mounted on the 35 stem 16 is a vaporizer 17, which comprises an annular member 17^a, having a downwardly-extending serrated rim 18, located to fit within the cup 13 when the valve 15 is seated. The valve 15 is normally held seated by a coiled 40 spring 19, surrounding the outer end of the stem 16 and bearing on the casing of the chamber 9 at one end and on a nut 20 at the

other. Air-passages 21 pierce the chamber 9 and permit air to flow in and mix with the gasoline.

55 In operation the gasoline flows through the pipe 4 into the chamber 1 until it reaches the mouth of the overflow-pipe 5. The valve 2 is open when the engine is running, and the gasoline then flows from the chamber 1 through the connection 7 and into the cup 13. Each time the valve 15 is unseated the vaporizer 17 is raised out of the liquid gasoline in the cup 13. A thin film of the liquid adheres to the rim 18, which is immediately vaporized 60 by the inrushing air through the passages 21.

65 I do not wish to be limited as to details of construction, as these may be modified in many particulars without departing from the spirit of my invention.

70 Having described my invention, what I claim as new, and wish to secure by Letters Patent, is—

1. In a carbureter, the combination with a chamber constructed to be connected to an engine and having air and gasoline connections, of a gasoline-cup mounted in said chamber, a valve bearing a vaporizer located to normally dip into said cup and to be lifted out of said cup when said valve is unseated, substantially as described.

75 2. In a carbureter, the combination with a chamber constructed to be connected to an engine and having air and gasoline connections, an annular cup located in said chamber, a valve bearing a vaporizer dipping into said cup when said valve is seated and being withdrawn therefrom when said valve is unseated, substantially as described.

80 3. In a carbureter, a vaporizer comprising an annular member mounted on a valve-stem and bearing a serrated rim thereon, substantially as described.

85 4. In a carbureter, a cup, and a vaporizer bearing a serrated rim constructed to fit into said cup, substantially as described.

90 In testimony whereof I have hereunto set my hand in presence of two subscribing witnesses.

GEORGE A. GRAVES.
